United States Patent Office

Des. 221,385

Patented Aug. 10, 1971

221,385

COMBINED ELECTRIC GUITAR AMPLIFIER AND LOUDSPEAKER HOUSING UNIT OR SIMILAR ARTICLE

Charles A. Ross, Chanute, Kans., assignor to Kustom Electronics, Inc., Chanute, Kans.

Filed Apr. 9, 1970, Ser. No. 22,342

Term of patent 14 years

Int. Cl. D14—01, 04
U.S. Cl. D26—14

The figure is a front perspective view showing my new design.

The side which is not shown is the same as the side that is shown, while the back and bottom are plain.

I claim:

The ornamental design for combined electric guitar amplifier and loudspeaker housing unit or similar article, as shown and described.
